A. Blasham,
Attorney.

UNITED STATES PATENT OFFICE.

LEONARD ATWOOD, OF BOSTON, MASSACHUSETTS.

INTERNAL-COMBUSTION ENGINE.

Application filed August 27, 1920. Serial No. 406,329.

To all whom it may concern:

Be it known that I, LEONARD Atwood, a citizen of the United States, and a resident of Boston, in the county of Suffolk and Commonwealth of Massachusetts, have invented certain new and useful Improvements in Internal-Combustion Engines, of which the following is a full, clear, and exact specification.

10 This invention relates to internal combustion engines especially designed for actuation by heavy fuel oils. It has for its objects the effecting of improved means for cooling the piston, for delivering the fuel oil to the cylinder, for reversing the engine, and for improving its general details of construction.

15 The drawing forming part of this specification shows in elevation, largely sectional, an engine embodying my improvements.

20 The piston in this engine is a chambered cylinder 1 having a shoulder 2 and an elongated neck 3, both the neck and shoulder being tubular. The piston is slideable in the cylinder 6 and also through the flange 7 whose annular shoulder 9 is attached to and supports the cylinder 6, this shoulder providing an annular space 10 into which the exhaust is designed to discharge, and to 25 be conducted therefrom through an exhaust pipe 11.

25 The upper end of the cylinder 6 is closed by a head 12 which is provided with a depressed central portion 13 as hereinafter set forth.

30 The lower portion of the neck 3 fits liquid tight in a pump cylinder 14 whose bottom end is provided with an intake port 15 and an outlet port 17, the port 15 being supplied with water through a pipe 19, and the outlet 35 17 discharging through a pipe 20. As the plunger-neck 3 reciprocates within the cylinder 14 with the action of the piston 1, the water within the cylinder 14 will be alternately forced up into the chamber 5 and withdrawn therefrom through the opening or channel 4. To provide a circulation of fresh water, a pipe 21 is connected at its lower end with the intake port 15, and its upper end opens into the chamber 5. Now 40 when the piston rises, water will be admitted from the port 15 into the chamber 5 to take the place of that descending through the channel 4; and when the piston moves downward, the chamber 5 being already

full, water below the plunger 3 will be forced out through the exit valve 17. In this way, a circulation will be maintained to and from the piston chamber which will effectually keep the latter at a suitably low 45 temperature to prevent it from burning the lubricating oil supplied to its outer surface.

50 The piston, although not itself provided with packing rings, is prevented from leakage by means of three packing rings 22, 23 seated in the lower end of the cylinder 6 with a backing ring 24 behind them preferably composed of brass, and held in place by an annulus 25 beneath them. The ring 23 is formed with an annular groove 26 into which fuel oil is fed through a hole 27 in the ring 24 from the receptacle 29. By means of compressed air within the receptacle, maintained by any suitable means, as a pump 30 whose piston 31 is actuated by 55 connection with the piston-neck or shoulder 2, the fuel oil is forced through the pipe 32 and hole 27 and thence out from between the rings 22, 23 into contact with the surface of the piston 1, such pressure being only sufficient to cause the fuel to move freely to the piston.

60 For discontinuing the oil-feeding at all times except during the upward movement of the piston, the reservoir 29 is provided with a valve 33 periodically shutting off the accession of oil to the pipe 32 by means of an elongated stem 34 pressed down upon its seat by a spring 35, the lower end of the stem resting in a cup 36. The cup is held 65 from horizontal displacement by an arm 37 pivoted at 39 to the engine frame, but is given an upward thrust by the cam-arm 40 upon which it rests. The latter is in its turn supported upon the periphery of the disk 41 having a projection 42 projecting from its face, this disc revolving in unison with the drive shaft 43. During a certain period of its revolution, which accords with the upward movement of the piston, the projection 42 engages the under edge of the cam-arm 40 and elevates it sufficiently to open the valve 33, and to hold the same open until the projection 42 has moved through approximately a quadrant and reaches the end 44 of the arc 45. At this point the cam-arm 40 drops and permits the closure of the valve 33, thereby terminating the feeding of oil to the cylinder.

65 70 75 80 85 90 95 100 105 110 As illustrated, the cam-arm 40 is posi-

tioned for the rotation of the drive shaft in the direction of the arrows shown. For feeding oil to the engine to run in the opposite direction, the cam-arm 40 is pivoted to a lever 46 which, being swung over toward the right, presents the portion 47 of the cam-arm to the action of the projection 42 and consequently causes oil to be fed only during the upward stroke of the piston when the drive shaft is reversed in its direction, suitable locking means as 49 being provided for retaining the lever 46 in its set positions.

To protect the packing rings 22, 23 against the action of the hot exhaust, the cylindrical wall of the piston 1 is prolonged to a height sufficient to shield these rings when the piston is in its lowermost position, but, as this will also close the discharge of the exhaust to the annular space 10, this prolonged wall 50 is pierced with numerous openings 51 sufficient in number, and located to permit the escape of the exhaust.

This construction serves in addition, two other functions, one being to keep the packing rings from injury by the blow of the piston-end were there no such prolongation, and the other being that of receiving and conveying into the upper section of the cylinder 6 a correspondingly increased area 30 of oil-film deposited thereon from between the packing rings 22, 23.

The purpose of the centrally depressed portion 13 of the cylinder head 12 is to substantially fill the space within the prolongation 50 during compression.

The combustion cylinder 6 is made a sufficiently loose fit for the piston to permit the oil-film on the latter to be volatilized by the heat of the cylinder and to pass to the space above the piston.

Compressed air is admitted to the annular space 10 at the moment the openings 51 descend thereto, both for aiding in the scavenging of the cylinder and for supplying the oxygen required for the proper combustion of the fuel oil. The air may be taken from the pipe 32' running from the air pump 30 to the reservoir 29, through a connection 53 closed by a valve 54 controlled by a bar 55 attached to the member 56 which carries the piston 31.

The operation of this engine is as follows: As the piston rises from the bottom end of its stroke, it carries up with it clinging to its peripheral surface a thin film of fuel oil delivered thereto from between the rings 22, 23, together with the air received from the pipe 32'. This film of oil quickly vaporizes under the influence of the heat of the cylinder 6 and is absorbed by the air, both being compressed to the degree required by the time the piston reaches the end of its up-stroke, which is a fraction of an inch below the depressed portion 13 of the cylinder-head. Then as the crank passes its upper

dead center the igniter 58 is caused in a well known manner to ignite the charge and force the piston downward. As the piston descends, fresh water is forced within it thereby reducing its temperature, until it reaches its bottom-stroke. Then the exhaust gases are expelled through the openings 51 and pipe 11 and compressed air admitted. As, under the influence of the fly wheel always employed in either four-cycle or two-cycle engines, the piston rises again, it carries with it the oil-film and air in the manner above described, the valve 33 lifting and fuel oil being forced to the annular groove 26 and between the packing rings 22, 23 into contact with the periphery of the piston. While thus rising, the water in the piston-chamber is partially withdrawn, causing a fresh supply to enter therein through the pipe 21, the descent of the piston having forced the water below it to escape through the exit 17.

Lubricating oil may be supplied from a reservoir 62 connected with the interior of the cylinder 6 by a tube 63.

Thus constructed, this engine will volatilize and burn any kind of fuel oil except those of low flash point such as gasoline, but all the heavy oils can be used with efficiency and great economy. The essential element of this engine is its process of producing an extensive area of oil-film and introducing the same into close proximity of a heated surface and thereby volatilizing the oil, no matter how heavy it may be. Another important feature is that of enabling the feeding of the oil to be reversed to accommodate the reversed engine, so that the engine cannot be accidentally run backward; in case the engine were reversed without shifting the lever 46, the oil would be fed during the down stroke of the piston and its vapor would escape through the exhaust manifold, and none would be supplied for the up-stroke.

I prefer to provide two pitmen 57 between the piston and crank pin 59, but I show only one of the two in the drawings, this one being pivotally attached at 60 to the ring 61 which is clamped about the shoulder 2. Inasmuch as the operative energy of the piston is always a downward thrust upon this collar and pitman, and the fly-wheel inertia always gives an upward thrust against this collar and piston, there is no need for a more secure attachment of the collar or ring 61 than that illustrated.

What I claim is:

1. An internal combustion engine comprising a cylinder, a piston reciprocative therewith, the diameter of said piston being less than that of the cylinder to provide a slight annular space between them, means carried by the cylinder for packing its open end to prevent the escape of the charge past the

piston, and means for introducing a fuel oil into said annular space during the return stroke of the piston.

2. An internal combustion engine comprising a cylinder, a piston reciprocative therein and of substantially less diameter, packing rings carried by the cylinder near its open end, and means for introducing a fuel oil between the cylindrical surfaces of the cylinder and piston during the latter's return stroke.

3. An internal combustion engine comprising a cylinder, a piston loosely fitting said cylinder and reciprocative therein, packing rings carried by said cylinder in contact with the periphery of said piston, and means for supplying fuel oil to percolate between said rings into viscous engagement with said piston.

4. An internal combustion engine comprising a cylinder, a piston loosely fitting said cylinder and reciprocative therein, packing rings carried by said cylinder in contact with said piston, one of said rings having a groove extending throughout its periphery, and means for supplying fuel oil to said groove.

5. An internal combustion engine comprising a cylinder, a piston loosely fitting said cylinder and reciprocative therein, packing rings carried by said cylinder in contact with said piston, an annular groove being provided between the periphery of certain of said rings and the cylinder, and means for supplying fuel oil under pressure to said groove.

6. An internal combustion engine comprising a cylinder, a piston loosely fitting said cylinder and reciprocative therein, packing rings carried by said cylinder at its lower end in contact with said piston, and means for feeding oil to said rings to pass between them into contact with said piston.

7. An internal combustion engine comprising a cylinder, a piston loosely fitting said cylinder and reciprocative therein, packing rings carried by the cylinder in contact with said piston, and a backing ring of soft metal between the peripheries of said packing rings and the cylinder.

8. An internal combustion engine comprising a cylinder, a piston loosely fitting said cylinder and reciprocative therein, an annular seat being formed in the lower end of said cylinder, packing rings located in said seat in contact with said piston, and a flange attached to the under end of said cylinder for keeping said packing rings in place.

9. An internal combustion engine comprising a cylinder, a piston loosely fitting said cylinder and reciprocative therein, an annular seat being formed in the lower end of said cylinder, packing rings located in said

seat in contact with said piston, a soft metal backing ring between the peripheries of said packing rings and said seat, and a flange attached to the under end of said cylinder for retaining said rings in place.

10. An internal combustion engine comprising a cylinder, a piston reciprocative therein, a drive shaft operatively connected with said piston, a closed reservoir, valve-controlled means for delivering fuel oil from said reservoir to said cylinder, and means moving synchronously with said drive shaft for opening said valve during the up-stroke of the piston, the same being shiftable for thus opening the valve in either direction of the shaft's rotation.

11. An internal combustion engine comprising a cylinder, a piston reciprocative therein, a drive shaft operatively connected with said piston, a reservoir for fuel oil, a valve-controlled means for delivering oil from said reservoir to said cylinder, a disk rotating synchronously with said shaft, a cam-arm concave downwardly riding on the periphery of said disk, means connecting said cam-arm and valve whereby the elevation of the cam-arm opens said valve, and a projection carried by said disk to engage the cam arm and to elevate it during the up-stroke of the piston.

12. An internal combustion engine comprising a cylinder, a piston reciprocative therein, a drive shaft operatively connected with said piston, a reservoir for fuel oil, a valve-controlled means for delivering oil from said reservoir to said cylinder, a disk rotating synchronously with said shaft, a cam-arm pivotally supported at one end, means for horizontally shifting this pivotal end, the free portion of the cam-arm being concave downward and riding upon the periphery of said disk, a projection from said disk for periodic engagement with said cam-arm for its elevation, and connection between said cam-arm and valve for opening the latter when the cam-arm is elevated.

13. An internal combustion engine comprising a cylinder having a centrally depressed head and an exhaust passage at its lower end a cylindrical piston loosely fitting said cylinder, packing rings carried by said cylinder in contact with said piston, said rings being close above the lower end of said cylinder, and means for delivering fuel oil into said cylinder close above certain of said rings, said piston having an apertured wall rising therefrom to cover said rings when the piston is at its lowermost point.

In testimony that I claim the foregoing invention, I have hereunto set my hand this 11th day of August, 1920.

LEONARD ATWOOD.
